WINDOW SASH

Jess Mayes, Buda, Tex.

Application November 25, 1935, Serial No. 51,515

1 Claim. (Cl. 20—42)

This invention relates to window sashes, one of the objects being to provide a sash which does not require the use of sash weights and is capable of being opened outwardly and raised so as to allow flow of air through both the upper and lower portions of the window opening.

A further object is to provide a sash which can be installed readily and requires few parts.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawings the preferred form of the invention has been shown.

In said drawings—

Figure 1 is an inner elevation of the sash in closed position within its window frame.

Figure 2 is a section on line 2—2, Figure 1.

Figure 3 is a section on line 3—3, Figure 2.

Referring to the figures by character of reference, 1 is a window frame in which is fitted a sash 2 capable of swinging outwardly therefrom but adapted to close against stop strips 3.

Fixedly attached to the frame 1 above the centers of the sides thereof are brackets 4 extending inwardly from the frame and these brackets carry rollers 5 at their free ends. These rollers are formed of wood or other suitable material, and are spaced apart a distance less than the width of the sash.

Secured to the stop strips 3 along those sides thereof facing each other are guides each comprising a metal strip 6 having parallel flanges 7 extended toward each other to provide slots 8 therebetween. The flanges farthest removed from the sash can be notched as shown at 9.

To the bottom portion of sash 2 at each side thereof is attached a plate 10 having a downwardly and laterally turned stem 11 projecting into the adjacent slot 8 and carrying a head or enlargement 12 whereby the stem can slide along the slot but cannot be withdrawn until after it has moved upwardly from the end of the guide.

A latch or other form of fastener 13 is attached to the sash so as to secure it in upright, closed position as shown by full lines in Figure 2. When it is desired to open the window the latch is disengaged and the upper portion of the sash swung inwardly until stopped by the rollers 5. The sash is thus supported in an inclined position affording top ventilation as shown by broken lines at A. To obtain full ventilation the lower end of the inclined sash is pushed upwardly, the stems 11 10 guiding it along the guides 6. The stems can rest in any of the notches 9 or can be brought to their uppermost positions at which time the sash will be supported in fully open position as at B.

Accidental upward withdrawal of the stems from the slots can be prevented by any suitable stop means. For example the fastening screws 14 can be employed for that purpose.

What is claimed is:

The combination with a window frame having a sill and guide members secured along the sides of the frame, of a sash adapted to close the frame, said sash normally resting upon and adapted to tilt outwardly on the sill, cooperating means on the frame and on the sash at its lower end for slidably connecting the sash and frame, said means including guide plates on the frame having longitudinal slots, stems on the sash slidable in the slots, means on the stems for holding them in the slots, means for fastening the sash in the frame, there being spaced notches in the slotted guides for engagement by the stems to support one end of the sash when in different open positions, and means supported away from the frame for limiting the outward movement of the sash while supported on and tilted outwardly relative to the sill and for supporting the sash in position for sliding movement toward or from the frame and in any one of a series of different inclined positions, said means including spaced, fixed brackets adjacent to the sides of the sash, and supporting elements on the brackets in the path of the sash when swung on the sill and under the sash when raised from the sill.

JESS MAYES.
